ADJUSTABLE FOOTREST

Anthony F. Lo Curto, near San Jose, Calif.

Application June 17, 1943, Serial No. 491,239

2 Claims. (Cl. 15—265)

The present invention relates particularly to the type of foot rest forming a part of the standard shoe-shining stand.

Insofar as is known to applicant stands of the character indicated are fitted with foot rests having a fixed height, rests or supports that are very satisfactory for individuals of average height. But those numerous individuals who fall within a different category, that is, those who are exceptionally short legged or exceptionally long legged find it extremely difficult to adapt themselves to this fixed height and at the same time assume a position that is comfortable and inconspicuous.

It is, therefore, one object of the present invention to provide a rest or support of the character indicated that may be quickly and easily adjusted to any desired height to properly accommodate persons of any size.

It is also an object of the invention to provide a device of the character indicated that will be simple in form and construction, economical to manufacture, strong, durable, and highly efficient in its practical application.

In the drawing:

Figure 1 is a side elevation of a device embodying my invention, with a part broken away.

Figure 2 is a sectional view on line 2—2 of Figure 1.

Referring now more particularly to the specific embodiment disclosed, I show at 1 a base member having a socket 2 formed therein to support a vertically disposed bar as 3.

The vertical shaft or support 3 has a vertical slot 4 formed lengthwise therein, and extending downwardly from the top to a point as 5 adjacent the bottom and parallel with the two sides 6.

Along one vertical edge of the shaft 3 are formed horizontally disposed and spaced sockets as 7, these sockets 7 consequently extending across the slot 4. The lower portion of each socket 7 has, in cross-section, the form of the segment of a circle and its upper portion slopes upwardly and outwardly to merge with the vertical edge in which the socket is placed.

At 8 is shown a rigid bar of any suitable material that is rectangular in cross-section and of suitable thickness to slide easily in the slot 4 and fitted on one end with a foot plate as 9. The lower or other end of the bar is provided with three pins as 10, 11 and 12 that extend laterally on both sides of the bar as shown. The pin 10 is proportioned to seat easily and solidly in any one of the sockets 7 and is placed in line with the forward edge of bar 8. The pin 11 is

placed directly opposite to pin 10 adjacent the rear edge of the bar, the two pins being spaced apart slightly more than the width of shaft 3.

The pin 12 is placed adjacent the same edge 10 as pin 11 and also near the adjacent end of the bar 8, being spaced from the pin 11 approximately the same as the spacing between pins 10 and 11. The spacing between the pins 11 and 12 is immaterial because pin 12 is merely a stop pin as hereinafter set forth.

In using the device the rigid shaft 3 is supported in a vertical position in any suitable manner with the socket 7 facing away from the seat in which the customer sits and not here shown.

- 15 If the customer is a long legged individual the bar 8 is thrust into the slot 4 with the pins 10, 11 and 12 in the position shown in dotted lines. The pins 11 and 12 are positioned to form a guide bearing against the rear edge of shaft 3, in which 20 position pin 10 is held in a position to slide easily up or down the shaft and past the sockets 7. In the case of the long legged individual the bar 8 is allowed to slide down shaft 3 to some suitable position as shown in solid lines where the pin 10 25 is permitted to fall into a socket 7. The bar 8 may be considered as a lever of either the first or second class, depending upon which pin, 10 or 11, is recognized as the fulcrum. Be that as it may, the weight of the bar alone urges it in the direction of the arrow 13 and automatically urges the pin 10 into a socket 7, at which time the pin 11 bears against the rear opposite edge of shaft 3 and positively limits the forward tilting of the bar. By swinging the bar 8 backwardly until both pins 11 and 12 contact the rear edge of shaft 3, the pin 10 is removed from the socket 7 and the bar 8 can be moved upwardly or downwardly as desired to a new position.

30 The mounting of bar 8 on shaft 3 is such that it will always extend upwardly beyond the upper end of the shaft 3 and be secured at an acute angle relative thereto. By means of this arrangement the foot plate 9 will be so positioned that the shaft 3 can offer no obstruction to the free movement of the hands of the operator during the polishing operation.

35 Although but one specific embodiment of the invention has herein been illustrated and described, it will be understood that various alterations in the details of construction and mode of assembly and operation may be made without departing from the scope of the invention as indicated in the appended claims.

I claim:

1. An adjustable foot rest of the character de-

scribed comprising, a rigid vertically disposed supporting bar having a slot formed therethrough extending from the top thereof downwardly to a point adjacent the bottom thereof parallel with its sides, and having a series of sockets formed in one edge thereof and extending laterally on both sides of said slot, and a lever proportioned to slidably engage said slot and having pins disposed laterally in one end and extending from both sides of said lever and a foot plate mounted on the other end of said lever, two of said pins being disposed at opposite edges of the lever and spaced apart slightly more than the width of said supporting bar, one of said pins being disposed to removably seat in one of said sockets and the other to seat against the supporting bar on the edge opposite to said sockets, and a third pin disposed in the lever in parallel relation to the last mentioned pin adjacent the end of the lever to form a stop to limit the swinging movement of 20 the lever when the first pin is disengaged from its socket.

2. An adjustable foot rest of the character described comprising, a rigid vertically disposed supporting bar having a slot formed therethrough extending from the top thereof downwardly to a point adjacent the bottom thereof parallel with its sides, and having a series of sockets formed in one edge thereof and extending laterally on both sides of said slot, and a lever proportioned to slidably engage said slot and having pins disposed laterally in one end and extending from both sides of said lever and a foot plate mounted on the other end of said lever, two of said pins being disposed at opposite edges of said lever and spaced apart slightly more than the width of said bar, one of said pins being disposed to removably seat in one of said sockets and the other to seat against the bar on the edge opposite to said sockets.

ANTHONY F. LO CURTO.
